SUPPORTING DEVICE

Fernan O. Conill, New York, N. Y.

Application January 8, 1937, Serial No. 119,697

10 Claims. (Cl. 132—36)

My invention relates to supports, and more particularly has reference to a supporting device for hair waving apparatus.

One of the objects of my invention is to provide a supporting member which is simple to construct, easy to repair and replace, and which can be manufactured at small cost.

Another object of my invention is to provide a supporting member which is freely movable from a horizontal to a vertical position, and having means for locking the supporting member in either position.

Another object of my invention is to provide a supporting member for hair waving apparatus which also serves as a conduit for carrying away any water contained in the apparatus.

With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which, for the purpose of explanation, have been made the subject of illustration.

In the drawings:

Figure 1 is a perspective view of a hair waving machine with my supporting device attached and in its operative position;

Figure 2 is a longitudinal sectional view of the supporting hand;

Figure 3 is a vertical cross section taken on the line 3—3 of Figure 2, looking in the direction of the arrows;

Figure 4 is a transverse sectional view of the swivel connection;

Figure 5 is a vertical sectional view taken on the line 5—5 of Figure 4, looking in the direction of the arrows;

Figure 6 is a cross sectional view taken on the line 6—6 of Figure 4; and

Figure 7 is a horizontal sectional view, partly in elevation, taken on the line 7—7 of Figure 4, looking in the direction of the arrows.

Referring to the drawing, Figure 1 shows a hair waving machine of my design which comprises a waving unit 1 connected with the neces-

sary operating media by a flexible conduit 2. The operating media is suitably housed in a casing 3 which is mounted on a base 4.

In the process of waving hair by my method, the operator uses the waving unit 1 to give the necessary treatment to the locks of hair. When not in use, however, such as for the purpose of separating locks of hair, or for binding those already treated, I provide a convenient rest for supporting the unit 1. This rest or support comprises the subject matter of the following specification.

The support comprises generally a trough-like supporting hand 5 attached to one end of a telescoping arm 6 which is attached to the casing 3 by means of a swivel connection 7.

The swivel connection 7 is shown in detail in Figures 4 to 7, inclusive, and comprises a plate 8 attached to the casing 3 at a convenient location by means of bolts 9. Fitted in an aperture 10 in the plate 8 is the reduced end 11 of a tapered pin 12. The end 11 is screw threaded to receive lock nuts 13 to securely hold the tapered pin in position.

A central bore 14 is provided in the pin 12 and extends partially therethrough to communicate with the interior of the casing 3. A spout or tube 15 is suitably fitted into the open end of the bore 14 and extends downwardly to communicate with a removable receptacle 16 in the base 4.

Rotatably mounted on the tapered pin 12 is a fitting designated generally by the numeral 17. This fitting comprises a hub portion 18 taper bored as at 19 to form a close fit on the tapered pin 12. The forward or smaller end of the pin 12 is reduced as at 20 and fitted with a washer 21 which bears against the face 22 of the hub 18. A nut 23 is screw threaded onto a further reduced portion 24 of the pin. The above structure provides a swivel connection which will be watertight, as will hereinafter be found necessary.

Integral with the hub 18 adjacent and at right angles to the bore 19 is a sleeve 26 which is in communication with the bore 14 of the pin 12 by means of a passage 27. This sleeve is adapted to have fixed therein one end of a tube 28 which is provided with an aperture 29 positioned adjacent the passage 27.

The tube 28 forms the fixed portion of the telescoping arm 6, the movable portion comprising a tube 30 which is of smaller diameter than tube 28 and is adapted to slide within it. A bushing 31 which is a close sliding fit on the tube 30 is fixed into the free end of tube 28 by 55

means of screws 32. The opposite end of the tube 28 is closed by a screw plug 33.

Mounted longitudinally within the tube 28 by means of screws 34 is a key 34. This key 34 coacts with a slot 35 formed in a split collar 36 attached to the end of the tube 30 which is within the larger tube 28 to prevent any rotary displacement of the two tubes. By reference to Figure 4 it will also be noted that the split collar 36 will, when the telescoping arm 6 is fully extended, abut the bushing 31 to prevent the two tubes comprising this arm from being separated.

The outer end of the tube 30 is fitted into a bore 37 in the base portion 38 of the supporting hand 5. The base portion 38 extends into an open trough 39 which terminates in a cup shaped end 40. The trough 39 is in communication with the tube 30 by means of an orifice 41.

By means of the above structure it will be seen that a conduit is formed leading from the trough 39 through tubes 30 and 28, aperture 29, passage 27, bore 14 and spout 15 to the receptacle 16 in the base 4 of the casing 3. When the waving unit 1 is not in use, small amounts of steam escape and condense. The moisture thus condensed is permitted to drain into this receptacle 16 through the passage just described as clearly shown in Figure 1 of the drawings.

To form a convenient rest for the waving unit 1, and to provide means for securely holding it in position, I provide a bracket 42. This bracket comprises a base 43 attached to the top of the base portion 38 of the supporting hand 5 and is provided with two upturned ends 44 and 45. The forward end 44 terminates in a semicircular fork 46 in which is adapted to rest the forward portion of the waving unit 1. The rear upturned end 45 terminates in a split ring 46' composed of a lower portion 47 and an upper portion 48 which are joined on one side by a hinge 49. The opposite or opening side of the ring 46' is provided with a spring operated latch 50. The ring 46' is adapted to receive the rear portion of the waving unit 1 and to securely hold it against displacement from the bracket 42 by the latch member 50.

It has been shown that the arm 6 is permitted to swivel and it will be noted from Figure 4 that its position may be changed from an operative position slightly above the horizontal to a vertical inoperative position. In order to hold the arm 6 in either of these positions, I provide an arm 51 which is integral with and extends radially from the hub portion 18 of the swivel connection 17. The free end of the arm 51 is provided with a bore 52. A plunger 53 having a reduced end 54 and a stem 55 is slidably fitted in the bore 52. A helical spring 56 is positioned behind the plunger 53 to normally force it outward from the bore 52.

The reduced end 54 is adapted to be received in either of two apertures 57 or 58 in the plate 8. The apertures are bored in an arc, the center of which is the tapered pin 12, and are spaced slightly more than 90° apart.

The exposed end of the plunger stem 55 is provided with an operating knob or button 59. To change the position of the arm 6, the operator removes the plunger 53 from either of the apertures 57 or 58 and moves the arm to the desired position. The plunger will then automatically fall into its aperture, thereby locking the arm in this position.

Thus it will be seen that I have devised a neat and efficient support which, when it is in its operative position, will provide a convenient rest for a hair waving unit so that this unit will always be in easy reach of the operator. In addition to this, it provides means to draw off all the condensed moisture from the unit. Moreover, when in its inoperative position, it may be folded to occupy a minimum amount of space.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In a device of the character described, a housing, an extensible arm pivotally mounted on the housing, and resilient means for holding the extensible arm in position.

2. In a device of the character described, a housing, an extensible arm pivotally mounted on the housing, and resilient means carried by said pivot to hold the extensible arm in position.

3. In a device of the character described, a housing, a swivel fixture mounted on the housing, an arm carried by the swivel, and means to hold the arm in position.

4. In a device of the character described, a housing, a swivel fixture mounted on the housing, an extensible arm carried by the swivel and means carried by the swivel to hold the arm in position.

5. In an apparatus for waving hair, a housing, a waving mechanism, a support for the waving mechanism, an extensible arm for said support, said arm being pivotally mounted on the housing, and means to hold the support in position.

6. In an apparatus for waving hair, a housing, a waving mechanism, a support for the waving mechanism, an extensible arm for the support, said arm being pivotally mounted on the housing, and means provided on the pivot for holding the arm in position.

7. In an apparatus for waving hair, a housing, a waving mechanism, a support for the waving mechanism, an extensible arm for the support, the arm being pivotally mounted on the housing, and means to hold the arm in position, said arm also serving as a conduit for removing any water in the waving mechanism to the housing.

8. In an apparatus for waving hair, a housing, a waving mechanism, a support for said waving mechanism, an arm for the support, said arm being pivotally mounted on the housing and means provided on the pivot to hold the arm in at least two different positions.

9. In an apparatus for waving hair, a housing, a waving mechanism, a support for said waving mechanism, an extensible arm for the support, said arm being pivotally mounted on the housing and means provided on the pivot to hold the arm in at least two different positions.

10. In an apparatus for waving hair, a housing, a waving mechanism, a support for said waving mechanism, an extensible arm for the support, said arm being pivotally mounted on the housing and spring actuated means provided on the pivot to hold the arm in at least two different positions.

FERNAN O. CONILL.
